UNITED STATES PATENT OFFICE.

HENRY F. MUELLER, OF NEW ORLEANS, LOUISIANA.

DESIGN FOR A COTTON-TIE BUCKLE.

SPECIFICATION forming part of Design No. 25,563, dated June 2, 1896.

Application filed April 29, 1896. Serial No. 589,609. Term of patent 14 years.

To all whom it may concern:

Be it known that I, HENRY F. MUELLER, a citizen of the United States, residing at New Orleans, in the county of Orleans and State 5 of Louisiana, have invented a new and original Design for a Cotton-Tie Buckle, of which the following is a specification.

This invention relates to a new and original design for cotton-tie buckles; and it has for 10 its object to provide a design of this character that shall be both useful and ornamental.

The leading feature of the design resides in a rectangularly-shaped body having a rectangular opening therein and reversely-disposed 15 L-shaped arms merging into the rectangular body at diagonally opposite corners thereof, said L-shaped arms having rounded outer ends and having their longer portions lying parallel with the adjacent sides of the 20 rectangularly-shaped body.

In the drawings, Figure 1 is a perspective view of a cotton-tie buckle embodying the herein-described design. Fig. 2 is a plan view thereof.

25 Referring to the accompanying drawings, 1 designates a rectangularly-shaped body essentially comprising the opposite parallel side

and end portions 2 and 3, respectively, said side and end portions of the rectangular body forming the boundary lines of a central rectangular opening 4, formed in the body. The 30 said rectangularly-shaped body 1 is provided with diagonally opposite rounded corners 5, and merging into the body at the other diagonally opposite corners thereof is a pair of 35 reversely-disposed L-shaped arms 6. The reversely-disposed L-shaped arms 6 at opposite sides and diagonally opposite corners of the body 1 are provided with outer rounded ends 7, and the longer portions of said L- 40 shaped arms lie parallel with the adjacent sides of the body and are shorter in length than the length of said body.

What I claim is—

The design for a cotton-tie buckle, herein 45 shown and described.

In testimony that I claim the foregoing as my own I have hereto affixed my signature in the presence of two witnesses.

HENRY F. MUELLER.
